[57] **CLAIM**

The ornamental design for a disposable faceshield, as shown.

DESCRIPTION

FIG. 1 is a top, front perspective view of a disposable faceshield showing my new design;

FIG. 2 is a top plan view thereof;

FIG. 3 is a side elevational view thereof;

FIG. 4 is a front elevational view thereof;

FIG. 5 is a rear elevational view thereof;

FIG. 6 is a vertical sectional view thereof, taken along line 5—5 of FIG. 5; and

FIG. 7 is a bottom plan view thereof.

U.S. Patent

Nov. 6, 1990

Sheet 1 of 3

D311,978

FIG. 1

FIG. 2

FIG. 3

FIG. 4

A perspective view of a curved, ribbed object, possibly a container or mold. The object has a flared top and a ribbed body. A dashed line with an arrow points to a specific detail on the side of the body.
